INVENTOR

R.E. Lewis *Victor J. Evans*

WITNESS

ATTORNEY

UNITED STATES PATENT OFFICE.

JOHN SWENKA, OF NORTH LIBERTY, IOWA.

GATE LATCH.

Application filed March 10, 1926. Serial No. 93,810.

The object is the provision of a simply constructed latch for either wooden or metal gates or other hinged members of a construction whereby the latch may be operated from either side of the gate and further wherein the parts constituting the improvement are housed and thereby protected from weather conditions.

To the attainment of the foregoing and other objects which will present themselves as the nature of the invention is better understood, reference is to be had to the drawings which accompany and form part of this application.

15 In the drawings:

Figure 1 is a top plan view of a gate provided with the improvement.

Figure 2 is a longitudinal sectional view through the improvement, the keeper for 20 the gate being also in section.

In Figure 1 of the drawings my improvement is illustrated in connection with a wooden gate, while in Figure 2 the device is applied to a metal gate. In both figures the 25 latch construction is the same.

Referring now to the drawings in detail, the numeral 1 indicates a gate or like swingable member and 2 the stop post therefor. In carrying out my invention I let in the 30 outer face of the post 2, the hollow substantially rectangular body portion 3 of a keeper. The keeper has side flanges arranged at opposite angles and which are indicated by the numeral 4.

Secured on the end of the gate by means 35 of there is the casing of my improvement. The center or body portion of the casing is substantially U-shaped, there being extended from the face plate 6 of the improvement, 40 plates 7 that provide the inner walls of housings 8. Each housing has its outer wall 9 formed with an angle extension 10 that is disposed a suitable distance away from the face plate 6, but in a line therewith. The 45 sides of the casing, between the face plate 6 and the walls 10, are open or partly open and there is pivoted in the compartments 11 provided between the said parts 6 and 10, one end of an operating lever 12. The pivots 50 for the levers are indicated by the numerals 13 and the parts of the levers inward of the pivots are arranged at an angle as indicated

at 14. The angle end of each lever carries a link 15 and each of these links is offset and passed through an opening or otherwise secured to the parallel arms 16 of the substantially U-shaped latch bar 17. The arms 16 are, of course, received in the housings 8 and the outer ends of the said arms are rounded upon themselves and extended in parallelism 55 with the arms proper, as indicated by the numerals 18. Secured to these extensions there are the ends of helical springs 19, the opposite ends of the said springs being fixed to the portion of the face plate 6 that covers the compartments 8. The rear ends of the rods 16 pass through openings in the closed walls 20 for the compartments 18.

By reference to the drawings it will be noted that the gate may be opened from either side thereof by operating either of the levers 12. It will be obvious that when the gate is swung to closed position the latch bolt or bar 17 will travel over the inclined flanges 4 of the keeper 3, after which the springs 19 70 will urge the said latch bolt into the keeper, thereby effectively locking the gate.

The simplicity and advantages of my improvement will, it is thought, be perfectly apparent to those skilled in the art to which such invention relates, when the foregoing description has been carefully read in connection with the accompanying drawings.

Having described the invention, I claim:

A gate latch, comprising a substantially 80 U-shaped member which is designed to surround the end of a gate and to be affixed thereon, said member having its parallel sides formed with outwardly extending housings, and the said housings being provided 85 with lateral extensions, whose ends are open, a substantially U-shaped bolt having its parallel arms guided through the housings, springs secured to the said arms of the bolt and to the housings for influencing the bolt 90 outward of the said housings, a link pivotally connected to each arm of the bolt and an angle lever pivoted in the mentioned lateral extensions of the housings, having handle portions arranged exteriorly thereof and having their inner ends pivotally connected 95 with the links.

In testimony whereof I affix my signature.
JOHN SWENKA.
